UNITED STATES PATENT OFFICE.

THOMAS A. DICKS, OF PITTSBURGH, PENNSYLVANIA, ASSIGNOR TO STANDARD STEEL PROPELLER COMPANY, OF PITTSBURGH, PENNSYLVANIA, A CORPORATION OF DELAWARE.

PROPELLER FOR AEROPLANES.

Application filed December 21, 1922. Serial No. 608,192.

To all whom it may concern:

Be it known that I, THOMAS A. DICKS, residing at Pittsburgh, in the county of Allegheny and State of Pennsylvania, a subject of Great Britain, have invented or discovered certain new and useful Improvements in Propellers for Aeroplanes, of which improvement the following is a specification.

The invention described herein relates to certain improvements in hubs for connecting the driving shaft to the blades of a propeller for aeroplanes. These hubs as at present constructed consist of a tubular body portion and socketed projections arranged radially of the hubs. It has heretofore been the practice to manufacture such hubs with the body portions and the projections in which the sockets are formed integral. In the manufacture of such hubs a piece of metal was forged to the approximate external shape and the body portion bored entirely through for the reception of one end of the shaft and the radial projections bored to to form sockets for the reception of the ends of the propeller blades. After the boring of the body portion and projections has been effected the parts must be finished internally so as to insure close fitting with the shaft and shanks of the blades and also externally. As the body portions and radial projections are integral the boring and finishing operations involve repeated handling of the structure. The present method of construction avoids in its manufacture the loss of metal removed in boring at the expense of the manufacturer.

The invention described herein has for its object a construction wherein a tubular body portion and a cross arm having means at its end for engaging the shanks of the blades are separable and wherein the said arm may be formed of semicircular sections. It is a further object of the invention to form body portion and arm in sections, the arm being constructed to clamp the sections of the body portions together. The invention is herein-after more fully described and claimed.

In the accompanying drawing which forms a part of these specifications, Fig. 1 is a sectional elevation of a propeller hub embodying improvements claimed herein; Fig. 2 is a sectional view on a plane indicated by the line II-II, Fig. 1; Fig. 3 is a sectional view on a plane indicated by the line III-

III, Fig. 2; Fig. 4 is a plan view of one of the arm sections; Fig. 5 is an end view of the body portion; Figs. 6 and 7 are views similar to Figs. 4 and 5 showing a modification in the construction of the arm and body portions; Fig. 8 is a sectional view showing the body portion of the hub and the arm formed in sections; and Fig. 9 is an end view of the hub and arm, one section of the arm being removed.

In the construction shown in Figs. 1, 2 and 3, the tubular body portion of the hub 1 is formed tapering internally for the reception of the correspondingly shaped end of the shaft and with a longitudinal groove 2 for the reception of the key or feather on the shaft. Externally the body portion is provided with peripheral seats 4 and 5 for the arm to the ends of which the blades of the propeller are secured. The seats or bearing portions 4 and 5 are spaced distances apart dependent on the diameter of the arm, and the surfaces of the seats are made irregular in cross-section so as to insure a positive driving connection between the body portion and the arm. As for example, in the construction shown in Figs. 1 to 5, the seats are made polygonal in cross section and the opening through the arm is correspondingly shaped, while in the form shown in Figs. 6 and 7 the seats are formed with the plurality of longitudinal ribs 6 and the walls of the opening through the arm are grooved for the reception of the ribs.

The cross arm is provided at its ends with suitable means such as sockets for the reception and engagement with the shanks of the blades and midway of its length an opening is formed through the arm for the reception of the body portion of the hub. The walls of the opening through the arm are constructed as hereinbefore stated to fit the seats 4 and 5 in the body portion. It is preferred that the arm should be formed by two longitudinally integral sections 7 and 8 semi-circular in cross sections. Through these sections and midway of their length are formed openings for the reception of the body portion of the hub the peripheral contours of these openings corresponding to the peripheral contours of the seats on the body portion as hereinbefore described. The positions of the members forming the arm longitudinally of the

body portion of the hub are determined by a collar 9 integral with the body portion and a nut 10 screwing on to the outer end of the body portion. In order to increase the area of contact of the members on the seats, flanges 11 are formed around the openings therethrough as shown in Figs. 1, 3, 4 and 6. Said flanges also serving to increase the longitudinal strength of the members. It is preferred to interpose rings 12 between the flanges 11 and the collar 9 and nut 10 respectively, and it is preferred that the flanges and the surfaces of the rings bearing thereon should be so bevelled that the rings will tend to force the flanges inwardly against the seats on the body portions.

The members forming the arm are held together around the shanks 13 of the blades by means of rings 14 screwing onto the threaded portions 15 of the members and also by preference by rings 16 screwing onto said members adjacent to the ends thereof as shown in Figs. 1 and 2. While any suitable means may be employed for holding the shanks from longitudinal movement in the sockets formed by the members when placed together, it is preferred to form annular recesses 17 in the members for the reception of enlargements or heads 18 on the shanks of the blades. In order to prevent any longitudinal movement of the shanks of the blades when engaged by the arm sections the shanks are formed with abutments *a* for the ends of the arm sections, and the heads or enlargements 18 on the shanks and the complementary walls of the recesses 17 in the arm sections are so beveled or inclined as indicated at *b* that when the arm sections are drawn together around the shanks the abutments on the shanks will be drawn firmly against the ends of the arm sections, as clearly shown in Figs. 1 and 2. While the grip of the members on the shanks would probably be sufficient to prevent any turning of the shanks in the sockets, it is preferred to employ pins 19 passing through the walls of the members into the heads 18 and held in position by the rings 14.

It is characteristic of the improvements claimed herein that practically all the stresses due to the centrifugal action of the blades are sustained by the arm or the members forming the arm. The members forming the arm can be formed to approximately finished shape and size by drop forging them, greatly reducing the cost of manufacture.

The body portion of hubs for propellers are subjected principally to stresses operating at an angle to each other. One set of stresses being those arising from the transmission of motion from the shaft to the blades can be termed circumferential stresses while the other stresses which are by far the greatest to which the hub is subjected

are due to the centrifugal force and there being two oppositely disposed blades there will be two sets of oppositely acting stresses tending to tear the arms from the body portion and to rupture the latter. As in the improved construction the body portion of the hub is not subjected to these centrifugal strains and as the circumferential or transmitting strains do not tend to pull the body portion apart, such body portion may be made in two semicircular sections or members, 20 and 21, as shown in Figs. 8 and 9. These sections or members may be brought to approximate shape and size by drop forging or by any other suitable method and in the finishing or machining operations seats or bearings 4* and 5* for the arm are formed on the sections and also a shoulder or abutment 22 against which the ring or band 23 will bear, this band serving as a support or bearing as against the movement in one direction of the members of the arm on the body portion, movement of the members in the opposite direction being prevented by a ring or band 24 which is held in position by a nut 25 screwing onto the outer end of the body portion. It will be observed that the sections or members of the body portion are held together by the walls of the openings through the members of the arm, by rings or bands 23 and 24 by the nut 25. If desired, a band or ring 26 may be shrunk or forced on the inner end of the body, thereby further reinforcing the body portion, as against any tendency to separate the sections by force. The body portion of the hub when made in sections, is preferably locked to the shaft by two keys engaging grooves in the respective sections of the body portions.

I claim herein as my invention:

1. A propeller hub having in combination a tubular body portion and a blade carrying arm consisting of two semicircular sections, said sections having openings therethrough intermediate their ends for the reception of the body portion and provided at their ends with means for positively engaging the shanks of blades.

2. A propeller hub having in combination a tubular body portion, a blade carrying arm consisting of two semicircular sections having their ends so constructed that when the sections are placed together the shanks of the blades will be positively gripped and having openings intermediate their ends for the reception of the body portion and means for holding the sections together.

3. A propeller hub having in combination a tubular body portion provided with spaced seats; an arm for carrying the blades, said arm having a transverse opening intermediate its ends for the reception of the body portion the walls of said opening being constructed to fit the seats in the body portion

- and means for preventing movement of the arm on the body portion.
4. A propeller hub having in combination with a tubular body portion; an arm for carrying the propeller blades consisting of two semicircular sections having openings intermediate their ends for the reception of the body portion, said sections being internally recessed adjacent to their ends; blades 10 provided with heads or enlargements adapted to fit in the recesses of the arm section and means for holding the sections together.
5. A propeller hub having in combination 15 a body portion consisting of semicircular sections, and an arm for carrying the blades of the propeller having a transverse opening intermediate its ends whereby the sections of the body portion are held together 20 by the arm.
6. A propeller hub having in combination a body portion consisting of semicircular
- sections; an arm adapted to carry the propeller blades consisting of semicircular sections and having openings intermediate 25 their ends for the reception of the body portion and means for holding the body and arm sections together.
7. A propeller having in combination a tubular hub or body portion, a blade carrying arm consisting of two semicylindrical sections having openings therethrough intermediate of their ends for the reception of the hub or body portion and provided on opposite sides of said openings with recesses, blade shanks adapted to be gripped by the arm sections and provided with heads or enlargements adapted to extend into said recesses in the arm sections and means for drawing said sections against the shanks. 30 35 40

In testimony whereof, I have hereunto set my hand.

THOMAS A. DICKS.
